UNITED STATES PATENT OFFICE

2,599,546

CARTRIDGE POSITIONER

James C. Elms, Altadena, Calif.

Application January 10, 1947, Serial No. 721,330

7 Claims. (Cl. 89—33)

(Granted under the act of March 3, 1883, as
amended April 30, 1928; 370 O. G. 757)

1

The invention described herein may be manufactured and used by or for the Government for governmental purposes without the payment of any royalty thereon.

My invention relates to improvements on automatic guns, particularly to a cartridge positioner providing means for aligning and separating two or more adjacent cartridges or other projectiles attached to one another by single flexible joints, or unattached one to the other, in the feedway of an automatic weapon.

Cartridges are usually fed to automatic guns of the Browning machine gun type, to which the invention is applied in the present instance though it is readily adaptable for use with other automatic guns, by means of a belt made up of a plurality of links so connected as to form a continuous belt connecting the cartridges. The linked cartridges are advanced step-by-step until each of the cartridges reaches an extraction position. At this point, a cartridge is extracted from its engaging link by means of an extractor and is moved toward its ultimate position in the barrel of the gun. The cartridges may also be fed to the gun unattached one to the other. Since the mechanism used in advancing a cartridge and extracting it to advance it into firing position is well known in the art, this mechanism is described herein only to the extent necessary to show its cooperation with my present invention.

Belt feed mechanism using the conventional disintegrating metal link belt, however, will jam easily if the belt is distorted or flexed in the flat plane that passes through the axis of the cartridges, and any appreciable rearward movement of the belt with respect to the gun brings the bases or rims of the cartridges together all the way up to the last cartridge in the receiving slot of the gun. Often, when the first cartridge moves into the receiving slot to be grasped by the fingers of the extractor which withdraws it from the belt, the base or rim of the following adjacent cartridge is in interlocking engagement with the groove just in advance of the rim on the proceeding cartridge. This may be even more common when cartridges are fed into the gun unattached to each other. Special booster devices, such as power driven notched discs for receiving the last few rounds in parallelism, are sometimes used, but these are somewhat complicated and expensive expedients as compared to the spacing device of the present invention.

The device of the invention consists of a small curved lever-pawl pivotally joined to a moving

2

link in turn pivotally joined to a non-moving piece. It is positioned in the bottom of the feedway of the weapon. When the first or leading round moves into a position where the extractor can draw it from the cartridge belt, the cartridge depresses the curved end of the lever, raising the other or straight end and the link to form an inverted V-shaped cam which separates the base of the succeeding adjacent cartridge so that the extractor-receiving groove cannot engage the rim or flange of the cartridge to be withdrawn. If the cartridges are linked together by a single flexible joint, two or my devices, one operating toward the front of the cartridges, the other operating toward the rear thereof, as shown in Figures 1 and 2, will align two cartridges and separate them the maximum amount allowed by the flexible joint. If only one device is used, the device operating toward the rear of the cartridge will separate the butt ends of the cartridges by a definite amount, while a single device operating toward the front of the cartridges will similarly separate the noses of the cartridges. If the cartridges are not linked together, two of my devices, one operating toward the front and the other toward the rear of the cartridges, will positively separate and align the two cartridges.

The principal object of my invention is to provide a device which will provide a means of aligning and separating two or more adjacent cartridges, attached one to the other by flexible joints, in the feedway of an automatic gun.

An important object of my invention is to provide a device which will align and separate two or more adjacent cartridges, unattached one to the other, in the feedway of an automatic gun.

Another important object of my invention is to provide a device for insertion in the feedway of an automatic gun which will prevent the grooves in the bases of succeeding adjacent cartridges becoming interlocked.

A further object of my invention is to provide a device for insertion in the feedway of an automatic gun which will position the leading cartridge in a flexible belt so that it may be withdrawn therefrom and carried to the barrel of the gun without jamming the gun.

A still further object of my invention is to provide a device which employs a small curved lever-pawl and a link pivoted thereon to be so positioned in the feedway of an automatic gun that one end of the curved lever is depressed when the leading cartridge moves into position to be withdrawn from the belt, to raise the other end of

said lever-pawl and link to form an inverted V-shaped cam separating the base of the succeeding adjacent cartridge so that its extractor-receiving groove cannot engage the rim or flange of the cartridge to be withdrawn.

An additional object of my invention is to provide a device of the character described to be inserted in the feedway of an automatic gun to prevent interlocking of the rims of succeeding adjacent cartridges which will be inexpensive to manufacture, easy to install, and readily interchangeable from right-hand to left-hand operational positions.

Other objects and advantages of my invention will become apparent during the following specification, and the accompanying drawings, forming part of the specification, wherein like numbers are used to designate like parts.

In the drawings:

Figure 1 is a side elevation of the transverse feedway of an automatic gun of the type specified, showing the invention in place.

Figure 2 is a plan view of the same, with the cover and all parts of the mechanism not pertinent to the functioning of the invention removed.

Figure 3 is an elevational view of the cartridge positioner, illustrating the manner in which it separates and aligns successive adjacent cartridges in the feedway of the gun, and

Figure 4 is an enlarged detail of the pivotal connections of the elements of the invention.

Referring now to the drawings, particularly to Figures 1 and 2, the numeral 5 designates the framework of an automatic gun having a hinged cover 6. Belt holding pawl brackets 7 are provided on the opposite sides of the said framework, each of the said brackets having a series of spaced lugs 8 which are traversed by removable pins 9, known in the art as "belt holding pawl pins." Belt holding pawls 10, provided with springs (not shown), are arranged in the space between two of the said lugs 8 facing a transverse feedway 11 along which an ammunition belt containing a plurality of cartridges 12 connected by a series of links 13 is advanced for engagement with an extractor 14 adapted to withdraw the leading said cartridge 12 from its engaging link 13 and move it to its ultimate position in the barrel of the gun. The pawls 10 function to restrain the cartridges against movement opposite to the feeding movement. All other elements of the gun mechanism cooperating with the afore-described elements have been omitted for clarity, as they are well known in the art and perform no function in connection with the operation of the invention.

The present invention includes a cartridge positioning device, indicated generally by the numeral 15, mounted on one of the pawl pins 9 in the spaces between certain of the lugs 8. The rearward said device 15 is mounted in a spaced recess 16 between the two of said lugs nearest the rearward end of said feedway 11 and is adapted to engage a cartridge 12 on the breech side of the links 13; a forward said device 15 would be mounted rearwardly of the forward lugs 8 and adapted to engage the bullet or projectile 17 secured in said cartridge 12.

The device 15 consists of a movable pawl or lever 18 curved at its left end as seen in Figures 3 and 4, a movable link 19 pivotally connected to the said pawl 18 in a slot 25 in the bifurcated straight end thereof by a pivot pin 20, and a non-movable member 21 provided with a hole 22 to

receive therethrough the pawl pin 9 to mount said member 21 thereon, said member having a leftwardly extending arm 23 to rest upon the bottom of the feedway 11 and to provide a pivot for the link 19 pivotally connected thereto in a slot 26 in the bifurcated end of said arm 23 by a pin 24.

The operation of the device is very simple. As a cartridge 12a (Fig. 3) is removed by the feeding mechanism, cartridge 12b is advanced to the right, and being confined by the top 27 of the feedway 11, it causes the link 19 and the pin end of the pawl 18 connected thereto to be depressed, allowing the cartridge 12b to pass to the right until it contacts the curved free portion of pawl 18, depressing it and forcing the pin end of said pawl 18 and link 19 pivoted thereon to move upwardly to form an inverted V-shaped cam, thereby providing a positive stop to separate the adjacent cartridges 12b and 12c when they have completed a cycle and have reached the respective positions occupied by 12a and 12b in Figure 3. Thus, when the fingers of the extractor withdraw the cartridge 12a from the belt links, they also remove the said cartridge from the curved end of the link-lever device, and the next adjacent cartridge 12b is free to be advanced into alignment with said fingers and the link-lever device is again forced between this cartridge and the next adjacent one 12c.

It is to be understood that the form of my invention herewith shown and described is to be taken as a preferred example of the same, and that various changes in the size, shape, and arrangements of the parts may be resorted to without departing from the spirit of the invention, or the scope of the subjoined claims.

Having thus described my invention, I claim:

1. A cartridge positioner of the character described for insertion in the transverse feedway of an automatic gun having a belt formed of a plurality of flexible links for feeding cartridges to said gun, comprising a member removably fixed on the framework of said gun, said member having an arm projecting into said feedway to form a fixed pivot therein, a pawl positioned in said feedway and at all times resting thereon, and a pivoted link connecting said fixed arm and said pawl, said pawl having a curved portion and being oscillated over said curved portion on said feedway upon engagement with a cartridge thereby raising simultaneously with said oscillatory movement the pivotal connection between said link and said pawl to provide a positive separation between said cartridge and the adjacent following one.

2. The structure of claim 1 wherein said pawl and said link form in said raised position an inverted V-shaped cone.

3. A cartridge positioning device for insertion in the transverse feedway of an automatic gun having means for feeding a plurality of cartridges to said feedway and an extractor for withdrawing said cartridges from their engaging links and for moving them into position in the barrel of the gun, comprising a stationary member removably mounted on the framework of the gun, a pawl, rectilinear in one part and curved in the other, and a link pivotally connecting said pawl to said member, said pawl having its curved part at its pivotal mounting which is urged in an upward direction upon engagement of a cartridge with the rectilinear part, whereby a positive stop is provided for the next following cartridge by the raised, curved part of said pawl.

4. The apparatus according to claim 3, wherein said rectilinear part rests upon the bottom of said feedway.

5. A cartridge positioning device for automatic guns including means for moving cartridges into the feedway of the gun and for moving them therefrom into the barrel of the gun, comprising a stationary member removably mounted on the framework of the gun, a pawl having a curved portion, and a link pivotally connected to said member and to said pawl at the curved portion thereof, said pawl being engaged by said cartridges in their movement through said feedway in a direction from said stationary member to said pawl thereby raising the pivotal connection between said pawl and said link upon movement of a cartridge over said pawl in the aforementioned direction and providing a positive stop for the next following cartridge.

6. A cartridge separating device for use in automatic guns having an automatic feed mechanism for feeding cartridges into the feedway and for moving them into the barrel of the gun, comprising a stationary member removably mounted on the framework of the gun, a pawl having a

5

curved portion and a rectilinear portion, a link, and means for pivotally connecting said link to said stationary member and to said pawl at its curved portion, said curved portion being raised upon engagement of said rectilinear portion by a cartridge, thereby providing a positive stop for the next following cartridge.

7. The apparatus according to claim 6 wherein said cartridges move in said feedway in a direction from said stationary member to said pawl.
